CARD TABLE COVER

Samuel J. Johnson, Cincinnati, Ohio, assignor to
 Clopay Corporation, Cincinnati, Ohio, a corporation of Ohio

Application October 12, 1932, Serial No. 637,566

3 Claims. (Cl. 45—68.3)

The subject matter of this invention is a paper fibre card table cover which is a new and useful article of manufacture by reason of its structure, design, and texture, which are coordinated to 5 suit the problems and convenience of the manufacturer, the merchandiser, and the user.

Paper card table covers have been frequently suggested and patented in the past, but few have ever been used practically, for the reason 10 that the articles suggested in the past have not been attractive and convenient. The general idea of paper card table covers in the past has been merely the provision of a cheap article which could be thrown away without much loss 15 at the end of a given session of card playing.

The idea of the present invention is to provide a paper fibre card table cover which affords the surface of the table better protection than the cloth or paper covers heretofore used, particularly against the ever present hazard of 20 drinks spilled as a result of the instability of the table. It is the intention of the present invention, likewise, to supply a card table cover which is more conveniently applied to the table 25 than previous covers, whether cloth or paper, which have been used as suggested in the past.

One great trouble with the idea of using paper card table covers in the past has been the fact 30 that most varieties of commonly used paper make a card playing surface highly unpleasant to the touch, and likewise difficult to play on because of the tendency of the cards to stick to it either by reason of high coefficient of friction between the cards and the card table cover, 35 or a tendency of the cards to stick to the cover by reason of partial vacuum created between the cards and the cover.

Another great trouble with the idea of paper card table covers is the fact that most paper 40 tends to curl, crumple, or crease, thereby making it almost impossible to pack or store the card table cover and still have anything fit to play on at the time of use.

The outstanding prerequisite to a successful 45 paper card table cover is that it may be sold at a reasonable price, such as ten cents retail. Most of the five and ten cent stores use accounting systems wherein an item must yield a profit 50 in relation to the space it occupies in the store, and it is therefore essential that a high class, tough, moisture resistant card table cover, manufactured from paper fibre be packable in very small space on the store shelves or display 55 counters in order to provide at once the high

quality article necessary, in combination with the low selling overhead.

The card table cover of this invention satisfies all of the foregoing requirements and the invention herein disclosed embraces two features: 60

The first feature is the quality of the material itself; and the second feature is the means for attaching the cover to the table, and these two features of the invention conjointly provide the fullest solution to the problems of providing an article which can be stored in small 65 space and yet provide a surface suitable for card playing.

Other objects and further advantages will be more fully apparent from a description of the 70 accompanying drawing, in which:

Figure 1 is a perspective view of the card table cover in packaged condition, certain parts being broken away for detail illustration.

Figure 2 is a plan view of the cover showing it 75 applied to a card table.

Figure 3 is a detail sectional view taken on line 3—3, Figure 2, showing the attachment device at the corner of the cover in relation to the 80 table.

Figure 4 is a detail sectional view taken on line 4—4, Figure 3, further illustrating the attachment device.

The material itself used for the fibre card table cover is a sheet 5 of relatively heavy, tough, 85 embossed or creped paper stock, finished to be highly moisture resistant.

At each one of the four corners of this sheet 5, which is preferably square, inasmuch as most card tables are square, is a reinforcing cardboard member 6 which is preferably secured to the sheet by stapling 7. This reinforcing member is preferably constituted by diagonally folding a square relatively heavy piece of cardboard 90 upon itself into the form of a triangle, its free corners 8 being disposed toward the center of the sheet. The sheet 5 has its corners folded over and turned under the diagonal or folded edge of the member 6, the staples 7 passing through the sheet and member 6. A tension 95 member, such as a rubber band 9, is secured to this reinforcing member, preferably passing between the staple and the diagonal fold of the reinforcing member along and within the fold.

When the card table cover is fastened to 100 the card table, by passing the rubber band 9 over each corner of the card table, (see Figure 3), it is held taut upon the card table, which tends to decrease any tendency to wrinkle or fold 105 or crease.

It will be observed that these tension members function as such for the reason that the corner reinforcing members to which the tension members are attached are positioned on the sheet

5 constituting the cover so that it falls just short of the corner. Therefore the rubber band looped over the corner pulls the reinforcing member toward the corner, thereby tending to obliterate all lines of fold to which the cover may have been subjected.

10 Figure 1 discloses the card table cover in packed condition. It is to be noted that it is folded upon itself into compact form, wrapped in transparent regenerated cellulose 10, and the package stiffened by a piece of cardboard 11 on which the name of the article, the price, and the complimentary legends may be printed. The cardboard 11 is apertured as at 12 in the form of a diamond which is representative of a perspective view of a card table top, the remainder of the table being drawn on the cardboard as at 13. Thus the table cover fills out the top surface of the table picture and the paper design and color are thus displayed.

15 20 25 The sheet of paper fibre is preferably very heavy and has the creping or embossing running transversely to the grain, whereby the tendency to curl or hold the creases occasioned by the method of compact packaging is very materially reduced. The creping or embossing is indicated by the lines 14. The grain since it is not readily visible is indicated, as to direction, by the double headed arrows in Figures 2 and 4.

30 35 40 The material has a very hard finish which enables the cards to slide over it very easily and lightly, and the presence of the creping or embossing prevents adhesion of the cards to the cover by reason of suction. The very unusual effectiveness and utility of the article is constituted by the combination of the heavy moisture resistant, non-creasing paper fibre sheet and the

tension imposing fastening means which reduce still further the tendency of the cover, while in use, to crease as a result of the condition which it was in while packed.

Having described my invention, I claim:

80 1. A new article of manufacture, comprising, a card table cover formed of a creped sheet of heavy, moisture resistant paper fibre, and means for securing said sheet to the card table, said means adapted to place said sheet, when in position on the table, under tension.

85 90 95 2: A card table cover, comprising, a heavy sheet of paper fibre, a reinforcing member stapled to it at each corner, said reinforcing member constituted by a piece of cardboard diagonally folded upon itself to form a triangle with the fold positioned to face the corner of the table to which the cover is to be applied, and a rubber band held by each reinforcing member between the fold and the staple which secures the member to the cover, the cover proportioned in relation to the card table so that the reinforcing member falls short of the corner of the card table and the rubber band when looped over the corner of the card table secures 100 the cover to it under substantial lateral tension adapted to reduce the tendency of the cover to crease as a result of having been folded for merchandising expediency.

105 3: As a new article of manufacture, a card table cover, comprising, a substantially rectangular sheet of hard finish, tough, moisture resistant paper creped transversely to the grain thereof, reinforcing members one at each corner of said sheet of paper, and rubber bands, one 110 associated with each reinforcing member, said rubber bands adapted to hold said sheet to the card table and to impose a lateral tension on the sheet to reduce creasing and fold lines.
